US0D1020365S

(12) **United States Design Patent** (10) Patent No.: **US D1,020,365 S**
(45) Date of Patent: ** Apr. 2, 2024

(54) **BLENDER ATTACHMENT**

- (71) Applicant: **SharkNinja Operating LLC**, Needham, MA (US)
- (72) Inventors: **Da Deng**, Newton, MA (US); **Trevor Patrick Dyment**, Boston, MA (US); **Noah William Weinstock**, Boston, MA (US)
- (73) Assignee: **SHARKNINJA OPERATING LLC**, Needham, MA (US)

(**) Term: **15 Years**

(21) Appl. No.: **29/837,862**

(22) Filed: **May 9, 2022**

(51) LOC (14) Cl. **31-00**

(52) U.S. Cl.

USPC **D7/412; D7/380**

(57) **CLAIM**

The ornamental design for a blender attachment, as shown and described.

DESCRIPTION

FIG. 1 is a top, front and left side perspective view of a blender attachment, showing our new design;

FIG. 2 is a right side view thereof;

FIG. 3 is a rear view thereof;

FIG. 4 is a left side view thereof;

FIG. 5 is a front view thereof;

FIG. 6 is a top view thereof; and,

FIG. 7 is a bottom view thereof.

The broken lines in the drawings show portions of a blender attachment and form no part of the claimed design.

1 Claim, 3 Drawing Sheets
